(57) **CLAIM**

The ornamental design for a lead frame, as shown and described.

DESCRIPTION

FIG. 1 is an enlarged fragmented perspective view taken along line 2 in FIG. 14 of a lead frame, showing my new design;

FIG. 2 is an enlarged fragmented view thereof taken along line 2 in FIG. 14;

FIG. 3 is an end view thereof taken along line 3-3 in FIG. 2;

FIG. 4 is an end view thereof taken along line 4-4 in FIG. 2;

FIG. 5 is an end view thereof taken along line 5-5 in FIG. 2;

FIG. 6 is an end view thereof taken along line 6-6 in FIG. 2;

FIG. 7 is an end view thereof taken along line 7-7 in FIG. 2;

FIG. 8 is an end view thereof taken along line 8-8 in FIG. 2;

FIG. 9 is an end view thereof taken along line 9-9 in FIG. 2;

FIG. 10 is an end view thereof taken along line 10-10 in FIG. 2;

FIG. 11 is an end view thereof taken along line 11-11 in FIG. 2;

FIG. 12 is an end view thereof taken along line 12-12 in FIG. 2;

FIG. 13 is a perspective view thereof;

FIG. 14 is a front view thereof;

FIG. 15 is a top view thereof;

FIG. 16 is a bottom view thereof;

FIG. 17 is a right side view thereof, the opposite side being symmetrical;

FIG. 18 is a rear view thereof;

(Continued)

FIG. 19 is an enlarged view thereof taken along line 19-19 in FIG. 16;

FIG. 20 is an end view thereof taken along line 20-20 in FIG. 14; and,

FIG. 21 is an end view thereof taken along line 21-21 in FIG. 14.

The Dash-Dot broken lines in FIG. 14 labeled as "2" are included to indicate the point at which the magnified view is cut off. The Dash-Dot broken lines define the bounds of the claimed design and form no part thereof. The Dash-Dash broken line portion of the figure drawings is included to show environment and form no part of the claimed design.

1 Claim, 8 Drawing Sheets
